CLAIM

The ornamental design for a clothes sleeve tensioning device, as shown and described.

DESCRIPTION

FIG. 1.1: Right side perspective view;

FIG. 1.2: Left side elevational view shown in use, partially inserted into a sleeve;

FIG. 1.3: Left side elevational view shown in use, fully inserted into a sleeve;

FIG. 1.4: Front elevational view;

FIG. 1.5: Top plan view;

FIG. 1.6: Bottom plan view;

FIG. 1.7: Left side elevational view;

FIG. 1.8: Cross-sectional view;

FIG. 1.9: Left side perspective view;

FIG. 1.10: Rear elevational view shown in use, fully inserted into a sleeve, with a bag of the device expanded by steam or hot air; and

FIG. 1.11: Rear elevational view.

The broken lines shown in the drawings illustrate environment and form no part of the claimed design. The right side elevational view is omitted because it is a mirror image of the left side elevational view. FIG. 1.8 is a cross-sectional view taken downwards at the center of the left side elevational view.
